UNITED STATES PATENT OFFICE.

CHARLES AUGUST GRUENHAGEN, OF CRESTON, CALIFORNIA.

ENVELOP.

SPECIFICATION forming part of Letters Patent No. 650,754, dated May 29, 1900.

Application filed March 1, 1899. Serial No. 707,384. (No model.)

To all whom it may concern:

Be it known that I, CHARLES AUGUST GRUENHAGEN, a citizen of the United States, residing at Creston, in the county of San Luis Obispo and State of California, have invented certain new and useful Improvements in Envelops; and I do declare the following to be a full, clear, and exact description of the invention, such as will enable others skilled in the art to which it appertains to make and use the same.

The invention has relation to envelops, and more particularly to that class in which a string is confined within the end of the envelop by means of which the envelop may be unsealed or opened by drawing outward upon one end of the string.

The object of the invention is to provide simple and inexpensive means for temporarily holding the free end of the string, thereby preventing the envelop being accidentally unsealed by the string becoming caught or tangled with other parcels or packages of mail.

With this object in view the invention consists in certain features of construction and combination of parts, which will be herein-after fully set forth.

In the accompanying drawings, Figure 1 is a side elevation of the reverse side of an envelop, showing the end of the string secured by the fastener. Fig. 2 is a sectional view through the envelop on the line of the fastener.

In the drawings, 1 denotes an envelop, which may be of any desired shape and construction.

2 denotes a string located in one end of the envelop and having one of its ends permanently secured in the lower corner of the envelop and its other end of sufficient length to project out of the envelop.

3 denotes a fastener which consists of an eyelet 4 and outer and inner disks 5 and 6,

respectively, which are held in position by the upsetting of the eyelet.

After the envelop has been sealed the free end of the cord or thread is adapted to be rove or wound around the eyelet under the disk 5, and in this position it would be impossible for the thread to be accidentally pulled or jerked, which would of course open or unseal the envelop. The inner disk 6 serves the means to prevent the eyelet tearing away from the envelop. I apply a sealing-wafer 7 to the disk 6 to prevent inspection of and tampering with the contents of the envelop through the eyelet.

From the foregoing description, taken in connection with the accompanying drawings, the construction, operation, and advantages of an envelop of this character will be readily appreciated without requiring an extended explanation.

Having thus described my invention, what I claim, and desire to secure by Letters Patent of the United States, is—

An envelop of rectangular form provided with the usual sealing-flap, and having a string located in one end of said envelop, one end of said string being permanently secured in the lower corner of the envelop; in combination with a fastener consisting of an eyelet 4 and inner and outer disks 5 and 6 respectively held in position by said eyelet, and a sealing-wafer 7 covering the inner disk 6 to prevent tampering with and inspection of the contents of the envelop through the eyelet, substantially as specified.

In testimony whereof I have hereunto set my hand in presence of two subscribing witnesses.

CHARLES AUGUST GRUENHAGEN.
